US00D660723S

(12) United States Design Patent
Akana et al.

(10) Patent No.: US D660,723 S
(45) Date of Patent:  May 29, 2012

(54) PACKAGING

(75) Inventors: Jody Akana, San Francisco, CA (US); Bartley K. Andre, Menlo Park, CA (US); Jeremy Bataillou, San Francisco, CA (US); Daniel J. Coster, San Francisco, CA (US); Daniele De Iuliis, San Francisco, CA (US); Evans Hankey, San Francisco, CA (US); Julian Hoenig, San Francisco, CA (US); Richard P. Howarth, San Francisco, CA (US); Jonathan P. Ive, San Francisco, CA (US); Duncan Robert Kerr, San Francisco, CA (US); Shin Nishibori, Portola Valley, CA (US); Matthew Dean Rohrbach, San Francisco, CA (US); Peter Russell-Clarke, San Francisco, CA (US); Christopher J. Stringer, Woodside, CA (US); Eugene Antony Whang, San Francisco, CA (US); Rico Zorkendorfer, San Francisco, CA (US)

(73) Assignee: Apple Inc., Cupertino, CA (US)

() Term: 14 Years

(21) Appl. No.: 29/387,395

(22) Filed: Mar. 11, 2011

Related U.S. Application Data

(63) Continuation-in-part of application No. 29/387,276, filed on Mar. 10, 2011.
(51) LOC (9) Cl. 09-03
(52) U.S. Cl. D9/737; D9/424
(58) Field of Classification Search D9/424, D9/425, 414, 737, 430-432; 206/568, 557, 206/307, 449, 456, 562, 486, 490, 564; 220/796; 229/406
